CLAIM

The ornamental design of the combined food jar and lid with downward curved side lifting handles, as shown and described.

DESCRIPTION

FIG. 1 is a perspective view taken from the upper, front, right-hand side of the combined food jar and lid with downward curved side lifting handles of the present invention; FIG. 2 is a perspective view taken from the lower, back, left-hand side of the combined food jar and lid with downward curved side lifting handles of FIG. 1; FIG. 3 is a side elevational view of the left side of the combined food jar and lid with downward curved side lifting handles of FIG. 1; FIG. 4 is a front elevational view of the combined food jar and lid with downward curved side lifting handles of FIG. 1; FIG. 5 is a side elevational view of the right side of the combined food jar and lid with downward curved side lifting handles of FIG. 1;

FIG. 6 is a rear elevational view of the combined food jar and lid with downward curved side lifting handles of FIG. 1; FIG. 7 is a top plan view of the combined food jar and lid with downward curved side lifting handles of FIG. 1; and, FIG. 8 is a bottom plan view of the combined food jar and lid with downward curved side lifting handles of FIG. 1.
